Primary Examiner — Messina L Smith*Assistant Examiner* — Rodolfo Castro, Jr.(74) *Attorney, Agent, or Firm* — Cantor Colburn LLP(57) **CLAIM**

The ornamental design for a television, as shown and described.

DESCRIPTION

FIG. 1 is a front perspective view of a television, showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is an enlarged view of the portion of the television labeled 8, shown in FIG. 1; and,

FIG. 9 is a rear perspective view of the television.

The dot-dot-dash broken lines encircling enlargement portions of the television form no part of the claimed design.

1 Claim, 7 Drawing Sheets(56)
